DYEING OF LEATHER

Joseph S. Kirk, East Greenbush, N.Y., assignor to General Aniline & Film Corporation, New York, N.Y., a corporation of Delaware

No Drawing. Application December 30, 1955
Serial No. 556,439

4 Claims. (Cl. 8—12)

The instant invention relates to improvements in the dyeing of leather, and more particularly to a process for dyeing certain types of leather with direct dyestuffs.

Leather which has been tanned with vegetable tanning extracts or with solutions of formaldehyde and a polyhydric phenol such as resorcinol or pyrogallol is difficult to dye with that class of colors known as direct dyestuffs. The leather is frequently dyed in an unsatisfactory manner, in some cases not taking up the dye, and in other cases yielding thin and spotty dyeings. Apparently, the tanning operation tends to render the leather resistant to direct dyestuffs.

It is an object of this invention to provide an improved process for dyeing leathers of the above-mentioned type with direct dyestuffs. Another object is the provision of a novel composition for the dyeing of such leathers with direct dyestuffs. Other objects and advantages will appear as the description proceeds.

The attainment of the above objects is made possible by the instant process which comprises dyeing leather tanned with a member of the group consisting of vegetable tanning extracts and aqueous solutions of formaldehyde and a polyhydric phenol of the group consisting of resorcinol and pyrogallol with a direct dyestuff from an aqueous dyebath at a pH of about 5½ to 7 containing about 0.1 to 5%, based on the weight of the leather, of a water-soluble non-ionic surface active condensation product having the formula

wherein R is a straight chain aliphatic hydrocarbon radical of from 16 to 18 carbon atoms and n has a value of about 12 to 18. It has been found that the use of the above defined dyebaths results in outstanding dyeings which are in general fuller, clearer, brighter and more uniform and/or level than dyeings produced without the assistance of the above defined non-ionic surface active agents. Moreover, the resulting dyed leather has an improved hand and feel, and is less brittle, harsh and raspy.

The process of this invention produces improved dyeing results when applied to leather which has been treated with vegetable tanning extracts. The treatment with vegetable tanning extracts and the effects thereof are well known in the art and no claim is made thereto per se. Vegetable tanning extracts contain tannins as their active principal, cutch, quebracho, gambier, myrobalan, chestnut and wattle extracts having been found to yield excellent results in the process of this invention. Vegetable extracts are usually applied in proportions of about 5 to 15% by weight of the leather for retannage of chrome leather and about 30 to 100% by weight of the skin for complete tannage.

The process of this invention is also applicable for producing improved dyeing results when applied to leather which has been treated or tanned with aqueous solutions of formaldehyde and resorcinol or pyrogallol. Such treatments are also well known in the art, as represented for example by the tanning process disclosed in U.S.

2

Patent No. 2,552,129. Such treatment generally involves application to the hides, skins, and pelts of an aqueous solution containing the formaldehyde and polyhydric phenol in respective molar proportions of at least 2:1 at a pH of about 0.3 to 3.0, as more fully described in said patent. It will be understood that instead of formaldehyde, there may be employed polymers of formaldehyde, acetaldehyde, crotonaldehyde, benzaldehyde, furfural and the like. Similarly, nuclear derivatives of resorcinol and pyrogallol may be employed, as for example hexylresorcinol, tertiary octylresorcinol, benzylresorcinol, phenylresorcinol, methoxyresorcinol, and the like. Mixtures of the aforementioned aldehydes and polyhydric phenols may also be employed, and the treatment may be applied in conjunction with other well known tanning treatments such as with vegetable tanning extracts, chromium sulfate, aluminum sulfate, zirconium sulfate, and the like.

The direct dyestuffs employed in the instant invention are also well known in the art, being generally of the anionic type resulting from the presence therein of carboxylic or sulfonic groups. It will be understood that the term "direct dyestuff" also includes those direct dyestuffs which are chromable by reason of containing metallizable groups capable of forming complexes with chromium. Highly satisfactory results are attained when such metallizable groups consist of an ortho-hydroxycarboxy configuration relative to an azo bridge as contained, for example, in azo dyestuffs produced with a paraaminosalicylic acid diazo component. Examples of direct, including direct chromable dyestuffs operative in the process of the instant invention are disclosed in the examples below. Other suitable dyestuffs include for example Fastusol Brown RTA (Pr. 365) and Direct Green YYD (C.I. 594). Since the process proceeds by exhaustion, the amount of dyestuff in the dyebath will be dependent upon the amount of leather treated, the depth of shade desired, and the like. Generally, proportions of about 0.1 to 5% of dyestuff by weight of the leather are usually employed for the production of light shades, 5 to 10% for medium shades and 10 to 20% for heavier shades. The dyebaths of the instant invention are employed in well known manner at temperatures ranging from about room temperature to 150° F., temperatures of about 120 to 140° F. being preferred. Best results are usually obtained by adding an acid, preferably organic, such as formic acid, towards the end of the dyeing process in order to complete the exhaustion of the dye on the leather. As stated above, the instant dyebaths are applied at an initial pH ranging from about 5½ to 7, although this pH may drop somewhat during the dyeing process due to acid substances in the leather being dyed.

From the above, it will be understood that the instant invention resides solely in the use, in the known processes for dyeing leather with direct dyestuffs, of about 0.1 to 5%, based on the weight of said leather, of a water-soluble non-ionic surface active agent of the type defined above. Optimum results are usually attained with about 1 to 3% of said surface active agent by weight of the leather. Dyebaths employed in carrying out the process of this invention usually contain about 0.2 to 3 parts of the said non-ionic surface active agent for each part of direct dyestuff, by weight. Said agents, and their methods of production are well known in the art and no claim is made thereto per se. Reference is made to U.S. Patent No. 1,970,578 for a disclosure of such surface active agents and their methods of production. In general, they may be produced by condensation of a higher fatty amine such as hexadecylamine, heptadecylamine, octadecylamine and their unsaturated analogs such as octadecenylamine and the like, or mixtures thereof, with 12 to 18 moles of ethylene oxide or equivalent. The above amine employed for condensation with ethylene oxide may be

derived in known manner from animal, vegetable, or mineral oils, fats and waxes, or in any other suitable manner.

The following examples, in which parts are by weight unless otherwise indicated, are illustrative of the instant invention and are not to be regarded as limitative. In the examples, Agent A is the condensation product of 15 moles of ethylene oxide with 1 mole of a mixture of amines consisting of about 30% hexadecylamine, 25% octadecylamine, and 45% octadecenylamine by weight. The resorcinol formaldehyde-alum tanned calfskin employed in the examples is produced by treatment of calfskin in a manner similar to that disclosed in Example 15 of U.S. Patent 2,552,129 employing alum instead of zirconium sulfate. It will of course be understood that leather produced in a similar manner but without the use of alum also yields improved results when dyed by the process of the instant invention.

In the following examples, a 5 g. sample of resorcinol-formaldehyde-alum tanned calfskin was wet back in 100 cc. water containing 2% Emulphor ON wetting agent (General Aniline & Film Corporation; polyoxyethylene ether of a higher fatty alcohol). The leather was rinsed and entered in a dyebath containing about 25 cc. water, .05 g. dyestuff and 1 g. of Agent A. The bath was maintained at 120 to 130° F. for 30 minutes, and then .025 g. formic acid was added. After maintaining the bath for another 30 minutes the leather was rinsed and dried. The results are tabulated below.

TABLE

Ex.	Dye	Identity	Results Without Agent A	Results with Agent A
1.	Fastusol Orange L3RA	Pr. 73	Level, fair color	Level, much stronger.
2.	Fastusol Orange L7G	Pr. 72	Level, fair good color	Stronger, fuller, brighter.
3.	Fastusol Brown 3RA	Pr. 95	Not level, fair color	Level, very full, bright.
4.	Fastusol Brown LBRSA	Pr. 47	Level, very good color	Very much fuller and redder.
5.	Fastusol Yellow LRTP	C.I. 814	Level, bright, fair color	Duller, much fuller.
6.	Fastusol Yellow LRRA	C.I. 814	Level, bright, good color	Do.
7.	Fastusol Brown LGA	Pr. 28	Not level, fair color	Level, very full.
8.	Fastusol Red 8BA	Pr. 246	Weak, spotty, fair color	Very full rich red.
9.	Fastusol Red 4BA	C.I. 278	do	Do.
10.	Fastusol Blue L7GA	Pr. 432	Dull, grayish blue, very poor	Stronger.
11.	Fastusol Blue LR	Pr. 443	Very little color, very poor	Full deep blue.
12.	Fastusol Blue LFBGL	Pr. 443	Spotty, little color, very poor	Level, full deep blue.
13.	Fastusol Green BA	Pr. 425	Spotty, very little color, very poor	Much better.
14.	Fastusol Turquoise Blue LGA	Pr. 278	do	Full bright turquoise.

The dyestuffs employed in the above table and their identity are listed in the 1954 Yearbook of the American Association of Textile Chemists and Colorists (AATCC). In all cases, the dyed leather had an improved hand and feel, and was less brittle, harsh and raspy when employing Agent A as compared with results obtained without the use of Agent A.

Example 15

The procedure of the above examples was repeated with the following dyestuffs, but employing a 5 g. sample of sheepskin mordanted with 10% of quebracho extract based on the set blue chromed weight instead of the resorcinol formaldehyde-alum tanned calfskin, .25 g. of dyestuff instead of .05 g. of dyestuff, and .09 g. of Agent A instead of .1 g. of Agent A.

Fastusol Orange L3RA
Fastusol Brown LBRSA
Fastusol Blue LR
Fastusol Red APA
Fastusol Green BA

A control set of dyeings was also carried out without the use of Agent A. In all cases, improved results with respect to levelness, clearness, fullness, brightness, and/or hand were obtained with the use of Agent A as compared with results obtained without the use of Agent A.

This invention has been disclosed with respect to certain preferred embodiments, and various modifications and variations thereof will become obvious to persons skilled in the art. It is to be understood that such modifications and variations are to be included within the spirit and purview of this application and the scope of the appended claims.

I claim:

1. In a process for dyeing leather which has been tanned with a member of the group consisting of vegetable tanning agents and aqueous solutions of formaldehyde and a polyhydric phenol of the group consisting of resorcinol and pyrogallol, the improvement comprising dyeing such leather with a direct dyestuff from an aqueous dyebath at a pH of about 5½ to 7 containing about 0.1 to 5%, based on the weight of the leather, of a water-soluble non-ionic surface active agent having the formula R—NH—(CH₂CH₂O)_nH, wherein R is a straight chain aliphatic hydrocarbon radical of from 16 to 18 carbon atoms and n has a value of about 12 to 18.
- 20 2. A process as defined in claim 1 wherein said non-ionic surface active agent is the condensation product of about 15 moles of ethylene oxide with 1 mole of a mixture of amines consisting essentially of about 30% hexa-
